United States Patent Office

Des. 203,968
Patented Mar. 8, 1966

203,968

VACUUM CLEANER

Robert C. Lagerstrom, Normal, and Joseph R. Mango,
Midlothian, Ill., assignors to National Union Electric
Corporation, Stamford, Conn., a corporation of Dela-
ware

Original design application June 26, 1964, Ser. No. 80,598.
Divided and this application May 12, 1965, Ser. No.
85,486

Term of patent 14 years

(Cl. D9—2)

FIG. 1 is a reduced perspective view of a floor-type vacuum cleaner embodying the features of our new design;

FIGS. 2 and 3 are upper and lower end views, respectively, of the cleaner shown in FIG. 1;

FIG. 4 is a top plan view;

FIG. 5 is a side view; and

FIG. 6 is a bottom plan view.

The dominant features of our design are shown in full lines.

This application is a division of our copending application Serial No. D 80,598, filed June 26, 1964.

We claim:

The ornamental design for a vacuum cleaner, substantially as shown and described.
